(57) CLAIM

The ornamental design for a buffet as shown and described.

DESCRIPTION

FIG. 1 is a front perspective view of a buffet showing the new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is another front perspective view thereof showing doors thereof in open configurations.

The broken lines shown in the figures illustrate portions of the buffet that form no part of the claimed design.

1 Claim, 6 Drawing Sheets# US D1,068,346 S
